UNITED STATES PATENT OFFICE.

STACY B. HASELTINE, OF CHICAGO, ILLINOIS, ASSIGNOR TO WILLIAM H. MINER, OF CHICAGO, ILLINOIS.

TANDEM DRAFT-RIGGING FOR RAILWAY-CARS.

1,357,776.

Specification of Letters Patent.

Patented Nov. 2, 1920.

Application filed August 22, 1919. Serial No. 319,065.

To all whom it may concern:

Be it known that I, STACY B. HASELTINE, a citizen of the United States, residing at Chicago, in the county of Cook and State 5 of Illinois, have invented a certain new and useful Improvement in Tandem Draft-Riggings for Railway-Cars, of which the following is a full, clear, concise, and exact description, reference being had to the accompanying drawings, forming a part of 10 this specification.

This invention relates to improvements in tandem draft riggings for railway cars.

One of the objects of my invention is to 15 provide a draft rigging of the tandem type in which the usual central stop members or posts and the intermediate thimble in the draft yoke may be eliminated. Other objects of my invention will appear from the 20 description thereof hereinafter following.

In the drawings forming a part of this specification, Figure 1 is a horizontal, sectional view of a draft rigging embodying my invention. Fig. 2 is a cross section taken 25 on the line 2—2 of Fig. 1. Fig. 3 is a perspective view of one of the followers,—in this instance, the rear follower.

Referring to the drawings, the numeral 10 indicates draft members or center sills, to 30 which the draft rigging is adapted to be applied. The front stop members are shown at 11—11 and the rear stop members at 12—12. The draft rigging is supported by the tie-plate 13 secured to the draft members 35 in a usual manner. 14 indicates a draw bar, only the rear portion thereof being shown, and 15 a draft yoke secured thereto. Within the draft yoke are mounted the front and rear followers 16 and 17, respectively. One 40 of said followers, as for instance, the front follower 16, comprises a transversely arranged plate 18 having rearwardly extended therefrom a preferably integral hollow housing 19 which in the particular form 45 shown in the drawing is provided laterally with the bracing members 20 shown integral therewith, and with a rear intermediate follower 32 which is preferably integral with the housing 19.

50 Within this housing the front spring 21 is mounted, consisting of an outer coil 22 and an inner coil 23. The said spring is forwardly seated against the front follower 16 and is rearwardly seated against the front 55 intermediate follower 24 which is also

mounted within the housing 19. The front intermediate follower is rearwardly provided with a recess 25 to receive the front end of the plunger 26 with which the rear follower 17 is provided. The rear follower 60 17 consists of a transversely arranged plate 27 having a forwardly extending casing 28 within which the rear spring 29, consisting of the outer coil 30 and inner coil 31, is mounted. The said spring is rearwardly 65 seated against the rear follower and forwardly seated against the rear intermediate follower 32. The rear intermediate follower is provided with a central perforation 33 for the passage of the plunger 26 which is in 70 preferable construction, integral with the rear follower 17. The casing of the rear follower is provided near its forward end with the lateral slots 34—34 within which the laterally extended guides 35 of the rear 75 intermediate follower may travel.

In normal position of the parts, as illustrated in Fig. 1 of the drawings, the rear intermediate follower is seated against the casing of the front follower and engages 80 the front intermediate follower. On rearward movement of the draw bar, the rear follower is held against retreating by the rear stop members, and the plunger 26 thereof holds the front intermediate follower in 85 its normal position, the latter resisting the rearward compression of the front spring, and the former resisting the rearward movement of the rear spring. The front spring, is compressed by the rearward travel of the 90 front follower, which also by reason of its actuation of the rear intermediate follower, compresses the rear spring. The rear intermediate follower moves rearwardly upon the plunger 26 and with its guides within 95 the slots 34 until it engages the rear of said slots indicated in Fig. 3 by the numeral 36, which limits the compressing movement of the parts and prevents the springs from being driven solid.

100 On forward movement of the draw bar, the front follower is prevented from retreating by the front stop members, the yoke draws the rear follower forwardly, the plunger forcing the front intermediate follower forwardly against the front spring which resists its movement and the rear intermediate follower is held against forward movement by the casing of the front follower, thus permitting the compression of 110

the rear spring between the rear intermediate follower and the forwardly moving rear follower, which movement may continue until the ends 36 of the slots 34 engage the rear intermediate follower, thus limiting the compressing movement of the parts.

I claim:

1. In a draft rigging for railway cars, in combination: front and rear main followers, an intermediate follower integral with one of said followers, a further intermediate follower and front and rear springs, each of said main followers having means slidably engaging an intermediate follower, the springs being mounted each between an intermediate follower and the opposed main follower, one of the main followers being provided with a plunger passing through one intermediate follower and engaging the other intermediate follower, the other main follower receiving the last mentioned intermediate follower within its housing.
2. In a draft rigging for railway cars, in combination: front and rear end followers, a spring housing on each of said followers, a spring within each housing, an intermediate follower for each of said springs, one of the intermediate followers being mounted within one housing, the other intermediate follower engaging the ends of said housing, the other housing being provided with a slot to slidably receive the last mentioned intermediate follower, and one of the end followers

being provided with a plunger passing 35 through one intermediate follower and engaging the other intermediate follower.

3. In a draft rigging for railway cars, in combination: alined housings, a main follower associated with each of said housings, 40 a spring within each housing, an intermediate follower received within one of said housings, and a further intermediate follower, one of said housings being provided with slots to slidly receive the last mentioned intermediate follower and a plunger to engage the first mentioned intermediate follower.

4. In a draft rigging for railway cars, in combination: a pair of intermediate followers, one of which is centrally perforated; a pair of springs; and two main followers, one of said main followers being provided with a casing within which to receive one of said springs, a central plunger passing 50 through said perforated intermediate follower and slots to slidly accommodate said intermediate follower; the other of said main followers being provided with a casing to receive the second spring and the other 55 intermediate follower, the latter being adapted to be actuated by the plunger upon relative approach of the main folowers.

In witness that I claim the foregoing I have hereunto subscribed my name this 8th 60 day of Aug., 1919.

STACY B. HASELTINE.
